UNITED STATES PATENT OFFICE.

JOHN F. BRADY, OF PROVIDENCE, RHODE ISLAND.

AUTOGRAPHIC REGISTER.

1,262,741.

Specification of Letters Patent. Patented Apr. 16, 1918.

Application filed July 19, 1916. Serial No. 110,226.

To all whom it may concern:

Be it known that I, JOHN F. BRADY, a citizen of the United States, and resident of the city of Providence, in the county of 5 Providence and State of Rhode Island, have invented certain new and useful Improvements in Autographic Registers, of which the following is a specification.

This invention relates to improvements in 10 autographic registers of the class provided with a plurality of strips of paper leading from as many rolls over a writing tablet, and the object of this invention is to provide a register of improved construction comprising a casing in which a draw is slidably 15 mounted, the latter being adapted to carry a large number of rolls of paper.

A further object of the invention is to provide a plate covering the writing tablet, 20 which when in operative position, serves as a rest for the hand of the writer, and also serves to engage the draw to lock and retain the same in closed position.

The invention further consists in 25 constructing both the casing and the sliding draw with two sheet metal side plates each folded on its upper edge to provide longitudinal grooves therein, these grooves in the draw member serve to hold the roll carrying 30 plates, whereby these plates are releasably supported and are adapted to be readily removed and replaced by others to support the desired number of rolls in the draw.

With these and other objects in view, the 35 invention consists of certain novel features of construction, as will be more fully described, and particularly pointed out in the appended claims.

In the accompanying drawings:

40 Figure 1—is a perspective view of my improved register showing the roll containing draw partly withdrawn from the casing.

Fig. 2—is a central sectional view 45 through the casing and draw showing the rolls mounted therein, one of said rolls being partly broken away to better show the plate in which the rolls are rotatably mounted.

Fig. 3—is a top view of the casing with 50 the cover plate removed, showing the writing tablet and the guide rolls over which the strips of paper are led.

Fig. 4—is a sectional end view on line 4—4 of Fig. 2.

55 Fig. 5—is a short portion of one of the

roll carrying strips with a tension spring shown as connected thereto.

Fig. 6—is a sectional view of one of the side walls of the draw showing the slotted angle plate held in the groove in the side 60 wall of the draw.

Fig. 7—is a perspective view of the slotted angle roll supporting plate.

Referring to the drawings 10 designates the body portion of my improved register 65 which is supported preferably on a wooden base 11. This casing is preferably formed with two side plates of sheet metal each having its upper edge 12 and its lower edge 13, bent outward and then backward upon itself 70 as best illustrated in Fig. 4 forming a longitudinal groove therein. A plate 14 forms the bottom of the casing and its edges 15 are secured in the corresponding grooves in the lower edge 13 of the side plates formed 75 to receive it. The grooves in the upper edge 12 of these side plates serve to support the roll carrying strips 16, see Fig. 3, in which the guide rolls 46 are mounted, the edges of which are inserted therein and retained by the screws 17. These grooves also serve to receive the opposite edges of the writing tablet 18 over which the strips of paper are drawn from the different rolls 19 between the carbons (not shown). 80

Posts 44 are provided in the tablet to enter corresponding holes in the sheets of carbon, and spring pressed fingers 45 serve to grip and retain the front edge of these carbon sheets. 85

The cover plate 20 is hinged at 21 in the ears 22 on the body portion and its face is cut away as at 23 to expose the face of the upper paper strip to be written on, and the plain surface 24 of the plate serves as a rest 90 for the arm of the person while writing.

The front end of this plate has a downwardly turned lip 25 for the purpose of engaging the front plate 47 of the draw to lock the same closed. A spring pressed 100 binding lip member 26 is hinged on the ear 27 on the plate 20 and may be raised against the pressure of the coil spring 28 by the operating handle 29 to permit the paper strips to be advanced.

One of the essential features of my improved invention is the construction of the draw 30 in which I am enabled to carry a large number of rolls 19 of paper, the number herein shown is five but any desired 110

number of rolls may be carried the same being limited only by the length of the casing and draw. This draw is constructed similar to the casing in that its side plates 5 31 are formed of sheet metal, each edge of which is first turned outward and then backward upon itself as at 32 and 35 forming a groove 33 at the top and at the bottom. The bottom groove serves to receive the 10 edges of the bottom plate 36 which are fastened therein while the top groove serves to receive the inwardly turned flange portion 40 of the roll carrying angle plate 38. This roll carrying plate may be constructed 15 of any desired length that is, long enough to accommodate the desired number of rolls, if two rolls are to be used, then the plate will be long enough to accommodate them, and longer plates may replace them when a 20 greater number of rolls is desired to be carried.

This plate has a downwardly extending body portion 39 and an outwardly turned flange portion 40 and is provided with 25 slots 41 preferably set on an angle to prevent the rolls from being withdrawn therefrom by the unrolling of the paper strips and these slots are placed the proper distance apart and are arranged to receive the 30 trunnions 42 of the different rolls. By constructing these plates in this way the flange portion 40 may be pressed into its groove at the top of this plate and by the friction of the upper lip is held securely in 35 position therein, at the same time being adapted to be readily removed and replaced by another of the length desired.

A light metal friction spring 49 is bent in a U-shape in cross section and has one of 40 its arms 50 riveted as at 43 to this angle plate, its free end 51 extends upward and is adapted to press lightly against the end of the roll 19 to control the unwinding of the paper strip therefrom. The middle portion 45 of this spring is removed as at 48 to permit the roll trunnion to extend therethrough

and a handle portion 52 is provided for withdrawing the spring from the roll.

By my improved construction this casing and draw may be formed of sheet metal 50 and at the minimum expense requiring but little machining and therefore it may be assembled very quickly and without the employment of skilled labor.

Having thus described one illustrative embodiment of my invention I desire it to be understood that although specific terms are employed they are used in a generic and descriptive sense and not for the purpose of limitation, the scope of the invention being 60 defined and limited only by the appended claims.

I claim:

1. An autographic register comprising a casing, a draw adapted to carry a plurality 65 of paper rolls slidably mounted in said casing the sides of said draw being formed of sheet metal each folded on its upper edge to provide longitudinal grooves therein, and roll supporting members mounted in said 70 grooves.

2. An autographic register comprising a casing, a draw adapted to carry a plurality of paper rolls slidably mounted in said casing, the sides of said draw being formed of sheet metal folded on its upper edge to provide longitudinal grooves therein, and roll carrying plates each provided with roll trunnion slots having a flange to fit said 75 grooves and be releasably retained therein. 80

3. An autographic register comprising a casing, a draw adapted to carry a plurality of paper rolls slidably mounted in said casing, the sides of said draw being formed of sheet metal strips each folded on its upper 85 edge to provide a longitudinal groove therein, roll supporting members mounted in said grooves and a spring carried by one of said members for applying tension to each roll.

In testimony whereof I affix my signature.

JOHN F. BRADY.
